UNITED STATES PATENT OFFICE

92,130

DESIGN FOR A STORM SASH VENTILATOR SET

William C. Hansen, Milwaukee, Wis.

Application November 25, 1933, Serial No. 49,869

Term of patent 3½ years

To all whom it may concern:

Be it known that I, WILLIAM C. HANSEN, a citizen of the United States, residing at Milwaukee, in the county of Milwaukee and State of Wisconsin, have invented a new, original, and ornamental Design for a Storm Sash Ventilator Set of which the following is a specification, reference being had to the accompanying drawing, forming part thereof, and in which,

Figure 1 is longitudinal section view through the ventilator, and

Figure 2 is a front elevational view of the ventilator.

Figure 3 is a perspective view on a reduced scale showing the appearance of the ventilator in the open position, the fragmentary portion of a window sash being illustrated in dotted lines.

I claim:

The ornamental design for a storm sash ventilator set, as shown.

WILLIAM C. HANSEN.
